ILLINOIS

FILLING MECHANISM

Application filed May 3, 1926. Serial No. 106,493.

Our invention relates to improvements in filling mechanisms, and it consists in the combinations, constructions, and arrangements herein described and claimed.

5 In machines which fill bottles, that have a certain amount of air pressure therein, with liquid, the air pressure increases with an equal rapidity to the increase of the liquid within the bottles.

10 An object of our invention is to provide means for releasing a desired amount of air pressure from a bottle at a predetermined point.

15 A further object of our invention is to provide a device of the type described which will shut off the air pressure supply into the bottles, close the liquid control valve, and free the bottles so as to permit a desired amount of air pressure to escape at a predetermined point.

20 Other objects and advantages will appear in the following specification, and the novel features of the invention will be particularly pointed out in the appended claims.

25 Our invention is illustrated in the accompanying drawings, forming part of this application, in which

Figure 1 is a sectional view of the device, parts thereof being shown in elevation,

30 Figure 2 is enlarged portions of the device, and

Figure 3 is a side elevation of a portion of the device.

35 In carrying out our invention, we provide a liquid tank 1 having a plurality of liquid control units 2 disposed therein. An air pressure supply pipe 3 is connected to each unit. A spring-pressed valve 4 which is disposed within each filling unit 2 tends to close the passageway which is in communication with the air pressure supply 3. The valve 4 is provided with an integral tube 6 which extends downwardly therefrom to a 40 point beyond the lower extremity of the filling unit 2. A filling tube 7 passes through the valve 4, the tube 6, and extends downwardly, having at its lower end a liquid control valve, not shown. A bottle-centering bell 8 is disposed concentric with the filling

tube 7 and is adapted to engage with the lower end of the tube 6.

The bottle-raising means consists of arms 9 pivotally mounted at one end to a movable support 10, and at the other end to connecting rods 11. The connecting rods 11 are operatively connected to cylinders 12 which are slidably disposed within bearings 13. The bearings 13 are mounted in a movable support 13'. Bottle supports 14 are disposed on the upper ends of the cylinders 12 and are adapted to receive bottles 15. A saucer-shaped support 16 is rigidly mounted upon a stationary support 17 and is provided with a tapering surface 18. The support 16 is cut away at 19 so as to receive cam plates 20 of the shape shown in Figure 2. The cam plates 20 can be secured to the support 16 in any desired manner. The ends 21 of the cam plates are tapered for a purpose hereinafter described. The arms 9 are provided with cam rollers 22 which are adapted to contact with the surface 18 of the support 16.

70 The means for holding each of the bottles in filling position consists of a latch 23 which is pivotally secured to the movable support 13' and provided with an integral projection 24 extending outwardly at right angles therefrom. The latches 23 are provided with seats 23' which are arranged to extend beneath the arms 9 for holding the arms, together with their respective cooperating parts, upwardly in filling positions. A rod 25 is rigidly secured at its lower end to the stationary support 17, and is provided with a knock-out stand 26 disposed upon the upper end thereof. The stand 26 is provided with downwardly extending ends 27 and 27' which are adapted to engage with pins 28 on the projections 24.

75 From the foregoing description of the various parts of the device, the operation thereof may be readily understood. The bottles 15 are placed upon the supports 14 as 80 their corresponding rollers 22 ride downwardly upon a cam strip 29 of the support 16. As the rollers 22 ride upwardly to and upon the surface 18 of the support 16, the bottles are also raised upwardly. During the 85 90 95 100

upward movement of each bottle, the bottle-centering bell 8 strikes against the lower end of the tube 6 and raises the valve 4 upwardly, thus permitting the air pressure to pass into the bottle. In this manner, liquid 30 is permitted to flow into the bottle under air pressure. As the liquid passes into the bottle, the air pressure therein gradually increases. The air pressure supply accumulates so as to temporarily retard the flow of liquid into the bottle, the result being that the bottle is not filled fast enough. To overcome this, and at the same time to release any unbalanced pressure in the bottle so as to fill the bottle to the same level and prevent any foaming when the bottle is released, it is necessary to release a part of the counter-pressure in the bottle. To accomplish this, the pins 28 engage with the downwardly extending end 27 and ride upon the upper surface of the knock-out stand 26. At the same time, the corresponding roller 22 passes up the inclined end of the cam plate 20. In this manner, the arm 9 is raised a sufficient distance to permit the latch 23 together with the latch seat 23' to swing outwardly about its pivot. The roller 22 is now free to ride downwardly on the cam plate 20. In this manner, the bottle is lowered a sufficient distance to close the valve 4, thus cutting off the air pressure supply into the bottle, and permitting a small amount of the air pressure to escape from the bottle. When this is completed, the roller 22 rides upwardly a sufficient distance to permit the latch to again swing beneath the arm 9 as the pin 28 thereon rides downwardly upon the end 27' and disengages therewith. The bottle is again held in filling position, and the bottle is permitted to be filled to a desired height.

It is obvious that as many cam plates 20 can be placed upon the support 16 as desired. A knockout stand 26 is provided for each cam plate 20 and the cam strip 29. The latches 23 are moved away from the arms 9 after the arms have been raised due to their rollers engaging with the cam strip or cam plates, and are held away until the arms are again raised by the cam strip or cam plates.

We claim:

In a device for filling with liquid, bottles containing air under pressure, a filling mechanism comprising a support having a cut-away portion therein, a cam strip disposed upon said support and having an outwardly bent portion receivable in said cutaway portion in said support, pivotal arms, cam rollers carried by said pivotal arms, means for operatively connecting each of said arms with a bottle, said cam rollers being arranged to engage with said cam strip for actuating said arms to move the bottles into filling positions, latches for engaging with said arms for holding said bottles in filling positions, a filling tube, a bottle-centering valve disposed for movement on said filling tube, a pressure

valve arranged to be engaged by said bottle-centering valve, and means for releasing the latches which hold the bottles in filling positions to permit the temporary withdrawal of the bottle whereby said bottle-centering valve is moved away from said pressure valve, thereby permitting a portion of the air in the bottle to be released prior to the complete filling operation. 70
